UNITED STATES PATENT OFFICE.

EDWIN M. ROSENBLUTH, OF PHILADELPHIA, PENNSYLVANIA.

DESIGN FOR A BICYCLE-LAMP BRACKET.

SPECIFICATION forming part of Design No. 28,700, dated May 24, 1898.

Application filed December 23, 1897. Serial No. 663,269. Term of patent 7 years.

To all whom it may concern:

Be it known that I, EDWIN M. ROSENBLUTH, a citizen of the United States, residing in the city and county of Philadelphia, in the State of Pennsylvania, have invented and produced a new and original Design for Bicycle-Lamp Brackets, of which the following is a specification, reference being had to the accompanying drawings, forming part thereof.

10 Figure 1 is a view in perspective of a bicycle lamp bracket showing my new design.

Figure 2 is a plan view of the same.

As shown in the drawings, the leading or material features of my design consist of an 15 arm A in the form of an approximately semi-circular curve, the outer extremity a^x of which is cylindriform, and the inner extremity of which is broadened to form a foot a, between the extremities $a' a^2$ of which exists a recess 20 a^3 the profile of which constitutes an arc of a

circle,—and of a plate B embodying a recess b the profile of which constitutes an arc of a circle, and the respective extremities $b' b^2$ of which are matched with the respective extremities $a' a^2$ of the foot, a, so that the recesses a^3 and b face each other and are approximately concentric.

Having described my invention, what I claim, and desire to secure by Letters Patent, is—

30 The design for a bicycle lamp bracket herein shown and described.

In testimony that I claim the foregoing as my invention I have hereunto signed my name this 21st day of December, A. D. 1897.

EDWIN M. ROSENBLUTH.

In presence of—

J. BONSALL TAYLOR,
F. NORMAN DIXON.
